UNITED STATES PATENT OFFICE.

JEAN F. WEBB, JR., OF NEW YORK, N. Y., ASSIGNOR TO THE INTERNATIONAL SIGNAL CO., INCORPORATED, OF NEW YORK, N. Y.

PILOW-SHOE.

1,145,283.

Specification of Letters Patent.

Patented July 6, 1915.

Application filed May 15, 1915. Serial No. 28,430.

To all whom it may concern:

Be it known that I, JEAN F. WEBB, Jr., residing at New York, in the county of New York and State of New York, have invented 5 certain new and useful Improvements in Plow-Shoes, of which the following is a specification.

My invention relates to certain new and useful improvements in train stopping apparatus of the type disclosed in the application filed by J. F. Webb, Sr., and myself on October 12, 1914, Serial No. 866,356, and the application filed by myself on April 27, 1914, Serial No. 834,867, and the present invention 10 has particular relation to the path clearing device or contact shoe which is designed to effect the co-operative connection between the track ramp and the train carried apparatus.

Practical tests and experimentation have 20 proven that adequate provision must be made for the removal of snow and ice from the ramp device in order to insure full electrical contact throughout the length of the ramp. In order that this may be accomplished with the greatest completeness and 25 efficiency, I have provided a contact shoe or plow which forms the subject matter of the present invention, and the essential characteristic of which is the provision of a set of 30 grooves or flutes on the underside of the plow shoe proper, so designed as to form auxiliary cutting edges to assist in the complete removal of snow and ice from the ramp and discharge the same to one side.

More specifically, the invention comprises 35 a shoe which is composed of a contact plate or shoe proper, the front edge, at least, of which is beveled to present a sharp plow member to the ramp to shave off the snow and ice, as it were, the under side or contacting face of the shoe proper being grooved to 40 leave a rib or ribs that preferably extend parallel to the front cutting edge of the shoe and have sharpened edges to complete the 45 removal of snow and ice that might remain on the track after the front cutting edge has passed, the shoe being supported by a neck that joins it with a head, by means of which the shoe is connected with the plunger of the 50 train carried apparatus.

In its more subordinate nature, the invention embodies those novel details of construction, combination and arrangement of parts, all of which will be first fully de-

scribed, then be specifically pointed out in 55 the appended claims, and illustrated in the accompanying drawings, in which:

Figure 1 is a perspective view of the preferred form of the invention. Fig. 2 is a top plan view of the same. Fig. 3 is an inverted plan view showing the location of the grooves and ribs. Fig. 4 is a central vertical longitudinal section and part elevation illustrating the manner of applying the shoe to the plunger of the train carried apparatus. Fig. 5 is an inverted plan view of a modified form of the shoe. Fig. 6 is an inverted plan view of a further modification.

In the drawing, like numerals of reference designate like parts in all of the figures, and by reference to the same, it will be observed that 1 designates the support of the train stopping apparatus in which the plunger 2 is vertically reciprocable, being held down by a spring that engages the 70 plate 6 which rests on the heads of the bolts 5. The plunger 2 has a bore 4 in communication with the train pipe of the air brake system and a counterbore 3 to receive the 75 nipple 12 of the head 10 of the shoe, the head 10 being secured to the plunger 2 by the bolts 5.

7 designates the shoe proper which is in the nature of a flat plate, the side faces 14 of which are preferably parallel to the direction of traffic, while the front and back edges are beveled at 13 and extend diagonally across the line of travel to present a shearing edge to the ramp 18 (see dotted lines Fig. 4) and shear off any coating of 85 snow, ice, or other material that may impair a good mechanical and electrical contact between the ramp and the shoe. The shoe proper 7 is supported by a neck 8, having strengthening ribs 9, from the head 90 10, it being understood that the shoe 7, neck 8, ribs 9 and head 10 are preferably integrally formed. The object of making the head 8 of a weakened construction is, in case of the encountering of a non-yielding 95 obstruction along the roadway, that the neck 8 will break to release the air from the bore 4 of the plunger 2 via the bore 17 of the shoe and thereby set the brakes.

11 designates the holes, through which 100 the bolts 5 pass, in the head 10.

It will be observed that the under face of the shoe proper 7 is provided with one or

more grooves 15 to provide sharp edges 16 to assist in cutting the snow and ice from the ramp 18 in the event that the front cutting edge of the shoe fails to remove all of 5 the material from the ramp. The grooves 15 are preferably made to extend parallel to the front cutting edge and in the preferred construction of shoe the shoe is made reversible, that is to say, the front and back 10 faces 13 are both beveled and either may be used as a front edge. Furthermore, this type of shoe is especially adapted for the purpose, because it will serve to clear the ramp whether the engine be running forwardly or backwardly. Instead of making 15 the shoe proper 7 of a general "diamond" shape in plan view, as indicated in Figs. 2 and 3, it may be shaped as indicated in Fig. 5, or as indicated in Fig. 6, the grooves 15* 20 being provided and extending parallel to the front edges 13* of the shoe.

From the foregoing description, taken in connection with the accompanying drawings, it is thought the complete construction, 25 operation and advantages of my invention will be readily understood by those skilled in the art.

What I claim is:—

1. A plow shoe comprising a shoe plate, 30 the front face of which is beveled to present a sharp cutting edge, the under face of said shoe plate being grooved to present auxil-

iary cutting edges and a support for said shoe plate.

2. In a device of the character stated, a 35 shoe plate having a front plowing edge, the under face of said shoe plate being grooved and a support projecting from the upper face of said shoe plate.

3. In a plow shoe, a shoe plate, a support 40 projecting upwardly from said shoe plate, said shoe plate having a beveled front edge extending crosswise, the under face of said shoe plate being grooved parallel to said front cutting edge.

4. In a plow, a shoe proper comprising a 45 shoe plate, the front edge of which is beveled and extending at an angle to the line of traffic, the under side of said shoe plate being grooved to provide auxiliary cutting edges, and a support extending upwardly 50 from said shoe plate.

5. In a path clearing device, a plow shoe comprising a head, a shoe plate and a connecting neck between the same, said shoe 55 plate having its front and back edges beveled to present shearing edges, the under face of said shoe plate being flat and grooved parallel to said shearing edges to present auxiliary cutting edges, substantially as shown and for the purposes described.

JEAN F. WEBB, JR.
